HUMIDIFIER

George A. Dole, Minneapolis, Minn.

Application July 27, 1940, Serial No. 347,921

4 Claims. (Cl. 237—78)

My invention relates to humidifiers and more particularly to a humidifier which is operated in connection with a suitable source of steam supply, for instance, a radiator in the steam heating system for an office building, a manufacturing plant, an apartment, a dwelling or the like. The steam heating system in which the improved humidifier is embodied may be either the ordinary pressure or a vacuum system having a slight pressure on the radiator.

It is an object of this invention to provide an extremely simple and highly efficient humidifier that can be very easily and quickly installed and connected to a steam radiator without tapping said radiator for a steam connection or making any changes whatsoever therein, or can also be attached by tapping into any steam supply.

A further object of the invention is to collect any condensation that may take place in the improved humidifier and re-evaporate the same, thus avoiding a drainage system.

A still further object of the invention is to provide a humidifier that will reduce the pressure of steam taken from a radiator and eliminate all noise therefrom.

Other objects of the invention will be apparent from the following description in connection with the accompanying drawing.

To the above end, generally stated, the invention consists of the novel devices and combination of devices hereinafter described and defined in the claims.

In the accompanying drawing, which illustrates the invention, like characters indicate like parts throughout the several views.

Referring to the drawing:

Fig. 1 is a fragmentary view in side elevation showing the invention embodied in a steam radiator;

Fig. 2 is a view of the controller in central vertical section, on an enlarged scale;

Fig. 3 is a view in transverse section taken on the line 3—3 of Fig. 2;

Fig. 4 is a view in side elevation of the distributor, the drain pan and the curtain, on an enlarged scale;

Fig. 5 is a view in transverse vertical section taken on the irregular line 5—5 of Fig. 4;

Fig. 6 and Fig. 7 are views in transverse vertical section taken on lines 6—6 and 7—7 of Fig. 4, respectively, on an enlarged scale;

Fig. 8 is a view in central vertical section, showing a different type of controller; and

Fig. 9 is a transverse section taken on the line 9—9 of Fig. 8.

The numeral 10 indicates a radiator forming a part of a steam heating system, not shown, and comprising a plurality of sections, each of which includes a plurality of columns. Formed with 5 the right-hand end section of the radiator 10, at the upper end portion thereof, is a boss 11 having an internally screw-threaded opening provided to receive the customary pet cock or an automatic air valve, not shown. Steam is conveyed through 10 the opening in the boss 11 to the improved humidifier as will presently appear.

Referring first to the invention shown in Figs. 1 to 7, inclusive, which includes a steam controller 12, a vapor distributor 13, and a co-operating drain pan 14 and a curtain 15 for collecting and re-vaporizing condensation. The controller 12 includes inner and outer concentric, vertically disposed, cylindrical shells or casings 16 and 17, respectively. These shells 16 and 17 are spaced the one from the other to form an air-tight insulating chamber 18 that completely surrounds the shell 16. This chamber 18 is filled with ground cork *x* or any other suitable insulating material.

25 A perforated pipe 19 extends axially within the shell 16 which is steam-tight and said shell is filled with ground cork *y* or any other suitable material that would act as a silencer for steam discharged into said shell through the pipe 19. 20 The pipe 19, at its upper end, has an imperforate section 20 that extends through the chamber 18 and the shell 17, at the top thereof and outwardly of said shell. A steam pipe 21 at its intake end has screw-threaded engagement with the boss 11 and said pipe is connected at its discharge end to the pipe section 20. Interposed in the steam pipe 21 is a control valve 22 and a check valve 23. The purpose of the check valve 23 is to prevent air from entering the radiator 10 from the controller 12 when there is no pressure on radiator 10.

The drain pan 14 and the distributor 13, which are relatively thin, are interposed longitudinally between the columns of certain of the sections of the radiator 10. Said drain pan 14 is loosely supported on the lower transverse portions of the respective sections of the radiator 10.

The distributor 13, which is above the drain pan 14 and of substantially the same length, has at its outer or intake end an expansion chamber 24. The perforated pipe 19 has at its lower end a radially extended imperforate section 25 which extends through the compartment 18 and the shell 17 and outwardly of said shell. A vapor pipe 26 connects the pipe section 25, at its outer

end, to the distributor 13 at its expansion chamber 24. The distributor 13 has in its top a narrow vapor discharge slot or orifice 27 which extends the full length of said distributor and its expansion chamber 24. Leading from the distributor 13, at its inner end and in the bottom thereof, is a very short depending drain pipe 28. The drain pipe 28 is arranged to discharge into the drain pan 14 at its inner end.

The curtain 15 which is vertically disposed between the distributor 13 and the drain pan 14 is made of blotting paper, or any other suitable absorbent material held in a marginal rectilineal copper frame 29. Said curtain 15 rests, at the lower edge of its frame 29, on the bottom of the drain pan 14 midway between the sides thereof and extends substantially the full length of said drain pan. The upper member of the curtain frame 29 extends into notches 30 in the lower end of the drain pipe 28 and thereby holds the curtain 15 upright midway between the sides of the distributor 13.

The operation of the improved humidifier may be briefly described as follows:

When the control valve 22 is open, live steam from the radiator 10 travels through the pipe 21, the valves 22 and 23, the pipe section 20 and into the perforated pipe 19 where it enters the shell 16 of the controller 12. Obviously, the pressure of the steam, upon entering the pipe 19 and the shell 17, is reduced and the reduced pressure and the cork *y* eliminates all noise of the steam escaping from the radiator 10. As a result of the reduction of the pressure of the steam entering the controller 12, a lazy vapor is produced and moves from said controller through the pipe section 25 and the pipe 26 into the expansion chamber 24 of the distributor 13.

Vapor in the expansion chamber 24 travels along the distributor 13 and then escapes through the slot 27 into the spaces between the sections and columns of the radiator 10. Air heated by the radiator 10 while passing upwards absorbs vapor escaping from the distributor 13 and the hot air, moisture laden, moves upwards into the room.

It may be here stated that steam taken from the radiator 10 is composed wholly of water and vapor delivered by the distributor 13 is also wholly water in vapor suspension, of substantially one hundred per cent (100%) relative humidity and practically at saturation point. Any condensation occurring between the radiator 10 and the delivery end of the distributor 13 will be precipitated through the spout 28 directly into the drain pan 14 or onto the curtain 15. Condensation collected in the drain pan 14, aided by the curtain 15, will be re-evaporated by the radiator heat into the air passing upwards through the radiator 10.

This re-evaporation of condensation collected in the drain pan 14 and held in the curtain 15 is highly important as it avoids the need of a drainage system. A drainage system for a humidifier would be expensive, especially when installed in an old building, and often the structure of such a building makes it impractical to install such a system.

Referring now to the controller 31 shown in Figs. 8 and 9, the numerals 32 and 33 indicate, respectively, inner and outer shells spaced the one from the other to afford an insulating chamber 34, that is filled with ground cork *x*' or any other suitable insulating material. A perforated coiled pipe 35 extends axially within the shell 32 and

has imperforate end sections 36 and 37, the former of which extends axially through the shells 32 and 33 at the top thereof and the latter of which extends radially through said shells 5 at the bottom thereof. The pipe end sections 36 and 37 correspond to the end sections 20 and 25 of the perforated pipe 19. The shell 32 is filled with ground cork *y*' that completely surrounds the pipe 35. The action of the controller 31 is the same as that of the controller 12.

In actual installation of the above described humidifier, the same may be automatically controlled, for instance, by attaching a solenoid valve to the steam pipe 21 and wiring it to a "Humitrol" 15 located on an adjacent wall. With the "Humitrol" pointer set at the per cent of humidity desired in the building served, the humidifier will operate or shut down so as to sustain the per cent desired.

The drawing illustrates a commercial form of the invention, but it will be understood that the same is capable of certain modifications as to details of construction, arrangement and combination of parts within the scope of the invention herein disclosed.

The noteworthy thing about the improved humidifier is that, given a proper steam supply, this small device will deliver moisture into a building at the rate of approximately one gallon each hour with a condensation of approximately one quart each twenty-four hours. This evidences that the drain pan purpose is to avoid the installation cost of a drainage system, as the humidity from a quart of condensation would be comparatively insignificant.

What I claim is:

1. The combination with a radiator and a steam supply therefor, of a humidifier means mounted on the radiator and including a long narrow closed distributor, one end portion of which is enlarged to afford an expansion chamber at the distributor steam inlet, said distributor having in its top a narrow orifice extending substantially the full length of the distributor, and means for taking steam from the radiator and discharging the same into the expansion chamber.

2. The combination with a radiator and a steam supply therefor, of a humidifier means mounted on the radiator and including a long narrow closed distributor having in its top a narrow discharge orifice extending substantially the full length thereof, means for taking steam from the radiator and discharging the same into the distributor at one end thereof, a long narrow drain pan directly under the distributor, and a curtain made of absorbent material between the distributor and the drain pan, said distributor having at its opposite end from its steam intake an aperture through which condensation in the distributor is drained onto the curtain and into the drain pan, the lower end portion of the curtain being in the drain pan for removing condensation therefrom by capillary attraction.

3. The structure defined in claim 2 which further includes a rigid marginal frame for the curtain, said frame loosely resting on the bottom of the drain pan and supporting the curtain therefrom, and means on the distributor releasably holding the curtain in an upright position.

4. The combination with a radiator and a steam supply therefor, of a humidifier means mounted on the radiator and including a long narrow closed distributor having in its top a

narrow discharge orifice extending substantially the full length thereof, means for taking steam from the radiator and discharging the same into the distributor at one end thereof, a long narrow drain pan directly under the distributor, and a curtain made of absorbent material between the distributor and the drain pan, said distributor having at its opposite end from its steam intake a short depending discharge spout through which

5 condensation in the distributor is drained onto the curtain and into the drain pan, said curtain having a rigid marginal frame loosely resting on the bottom of the drain pan and supporting the curtain therefrom, said discharge spout having in its lower end a notch into which the curtain removably extends for holding the same in an upright position.

GEORGE A. DOLE.
